UNITED STATES PATENT OFFICE.

JONATHAN T. BROWN, OF MARBLEHEAD, MASSACHUSETTS, ASSIGNOR TO
OLIVER A. MILLER, OF BROCKTON, MASSACHUSETTS.

DESIGN FOR A HINGE MEMBER FOR LASTS.

SPECIFICATION forming part of Design No. 34,732, dated July 2, 1901.

Application filed May 31, 1901. Serial No. 62,678. Term of patent 14 years.

● *To all whom it may concern:*

Be it known that I, JONATHAN T. BROWN, of Marblehead, in the county of Essex and State of Massachusetts, have invented and produced a new and original Design for Hinge Members for Lasts, of which the following is a specification.

This invention relates to a design for a hinge member for lasts.

○ The drawing is a perspective view showing my design.

The essential feature of my design consists in an oval base, from which projects a hub and two angular parallel webs arranged with 5 their perpendicular sides against said hub.

1 represents an oval base; 2, a hub projecting upward from said base. 3 represents two angular parallel webs. The base 4 of each web rests upon said base, while their perpendicular sides 5 rest against said hub. 20

I claim—

The design for a hinge member for lasts, substantially as shown and described.

In testimony whereof I have affixed my signature in presence of two witnesses.

JONATHAN T. BROWN.

Witnesses:

E. BATCHELDER,
P. W. PEZZETTI.
